US00D726163S

(12) **United States Design Patent**
Bekhradi et al.

(10) **Patent No.:** **US D726,163 S**
(45) **Date of Patent:** **** Apr. 7, 2015**

(54) **REMOTE CONTROL**

(71) Applicant: **Samsung Electronics Co., Ltd.**,
Suwon-si, Gyeonggi-do (KR)

(72) Inventors: **Hamid Bekhradi**, Clavesana (IT);
Christopher Bangle, Clavesana (IT);
Pietro Nume, Clavesana (IT); **Do-Sung Jung**, Seoul (KR)

(73) Assignee: **Samsung Electronics Co., Ltd.** (KR)

(**) Term: **14 Years**

(21) Appl. No.: **29/472,365**

(22) Filed: **Nov. 12, 2013**

(30) **Foreign Application Priority Data**

May 13, 2013 (KR) 30-2013-0025041

(51) **LOC (10) Cl.** **14-03**

(52) **U.S. Cl.**

USPC **D14/218**

(58) **Field of Classification Search**

USPC D14/167, 203.3, 218, 480.1, 496;
D13/168; D21/566; 345/163;
348/211.99, 14.05, 114, 734

(57) **CLAIM**

We claim, the ornamental design for a remote control, as shown and described.

DESCRIPTION

FIG. 1 is a front perspective view of a remote control showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front perspective view thereof in a user environment.

The broken lines illustrating portions of the remote control are for environmental purpose only and form no part of the claimed design.

1 Claim, 8 Drawing Sheets
